AUTOMOBILE DOOR AND WINDOW

Eric C. Wahlberg, Stamford, Conn., assignor to
 Electrolux Corporation, Old Greenwich, Conn.,
 a corporation of Delaware

Application June 22, 1946, Serial No. 678,558

5 Claims. (CL. 180—82)

1

My invention relates to electric actuating means for operating windows and locks, and is more particularly adapted for the operation of windows and door locks on vehicles, such as automobiles, although it is by no means restricted thereto.

One of the objects of my invention is to provide electrically operated means for raising and lowering the windows of an automobile, which means may be controlled by either the driver or a passenger sitting adjacent to the window.

Another object of my invention is to provide means controlled by a single switch, or any one of several switches, for simultaneously closing all of the windows which may be open. This is of particular advantage when leaving the car, as it does away with the necessity of manipulating a separate switch for each window.

Another object of my invention is to provide a system of electrically operated door latches whereby each door may be unlatched by a push button switch or the like operable from both inside and outside the door, the system including one or more key operated switches located on the exterior of the car body whereby the system may be rendered inoperative to unlatch any of the doors thus effecting the locking of the car. In addition, a switch may be provided within the car whereby an occupant thereof may lock all of the doors from the inside.

A still further object of my invention is to so interconnect the window actuator circuits with the door latching circuits that when the latter is rendered inoperative by the actuation of the aforementioned key control switch, the interior switches for raising and lowering the windows will also be inoperative, but preferably the exterior switch for simultaneously raising all of the windows will remain operative. Thus, if the car is locked with the windows left slightly open, which is frequently desirable in hot weather, an unauthorized person cannot open a window further by inserting a long stick or the like through a partially opened window in order to manipulate one of the interior switches.

An additional object of my invention is to provide safeguards whereby the system and its component parts cannot be damaged by improper operation, whether intentional or accidental.

Further objects of my invention will be apparent from the following description considered in connection with the accompanying drawings which form a part of the specification and of which:

2

Fig. 1 is a wiring diagram showing a preferred embodiment of my invention;

Fig. 2 is a cross-sectional view of an automobile door showing an electric switch operable from either inside or outside the car;

Fig. 3 is a view, partially in section, of an automobile door showing the switch and a solenoid operated latch;

Fig. 4 is a cross-sectional view taken through the solenoid latch and also showing the keeper; and

Fig. 5 is a view, partially broken away, of an automobile door including an electric motor and drive for raising and lowering the door window together with suitable limit switches for controlling the motor.

Referring more particularly to Fig. 1, reference character 10 designates any suitable source of current, such as the usual car storage battery.

20 One side of the battery is grounded at 12, while a conductor 14 connects the other side with the blade of a two position switch 16. The poles 18 and 20 of the switch 16 are connected to the poles 22 and 24 of a similar two position switch

25 26 by the conductors 28 and 30, respectively. The construction of each of these switches is such that the switch blade is always in contact with one of the poles and never remains in a neutral or open position. With the two switches in the position shown in the drawing a circuit is completed from the conductor 14 through the blade and pole 18 of switch 16, conductor 28 and the pole 22 of switch 26 to a conductor 32 connected to the blade of this switch. This circuit will be interrupted if either of the switch blades is

30 thrown to the opposite position and, if this is done, it will be again completed by either returning that blade to its original position or throwing the other blade to its opposite position.

35 40 While these switches are shown diagrammatically in Fig. 1, in practice they would be key operated and located one on either side of the car body, preferably adjacent to the front doors. Thus, the circuit controlled by these switches

45 50 may be opened by the use of a key from either side of the exterior of the car, and may be again closed by the use of the key at either the same or the opposite side of the car.

The conductor 32 leads to a single pole switch 34, located within the car and preferably accessible to the driver. The other side of switch 34 is connected to a conductor 36, to which are connected conductors 38 leading to each of the doors of the car. Each of these conductors is 55 connected into the door through a suitable flex-

ible lead or plunger connection, as is indicated at 40. Within the door the conductor is connected to a push button type switch 42 which is provided with suitable spring means for biasing it to open position. Such switch is shown diagrammatically in Fig. 1 and more in detail in Fig. 2. As shown in the latter figure the switch is of the plunger or limit type mounted on a bracket 44. Adjacent to the switch a rod 46 extends through the door and is provided with a handle 48 on the inside and a similar handle 50 on the outside. A spring 52 serves to bias the rod 46 to the left, as viewed in Fig. 2. The rod carries an arm or disc 54 which is arranged to strike and depress the plunger 56 on the switch 42 when the rod is moved to the right.

The other terminal of switch 42 is connected by means of a conductor 58 to the solenoid 60 of a magnetically operated latch in which the bolt 62 of the latch constitutes the armature. The solenoid is mounted in the door as shown more particularly in Figs. 3 and 4 and a spring 64 is provided for biasing the bolt 62 to latching position. As is usual, the bolt is provided with a beveled end 66 which cooperates with an inclined surface 68 on the keeper 70, thus causing displacement of the bolt to the left against the force of the spring 64 as the door is closed. When fully closed, the bolt 62 is projected by the spring 64 so as to latch behind the shoulder on the keeper, thus holding the door closed.

Each door is provided with a similar switch and magnetic lock, and the system so far described operates as follows:

With the circuit through the switches 16 and 26 closed, and with the switch 34 closed, any of the solenoids 60 may be energized so as to retract its bolt by closing the respective switch 42. If a person within the car wishes to open a door, the handle 48 is pushed inwardly so as to depress the plunger 56 of the switch 42, thus closing the circuit to the solenoid. This inward pressure on the handle 48 also serves to swing the door open as soon as the bolt is withdrawn. In order to open the door from the outside the handle 50 is grasped and pulled outwardly, thus closing the switch in the same manner and causing the solenoid to withdraw the bolt. The pull on the knob 50 from the outside of the door also serves to swing the door outwardly as soon as the bolt is released. When the door has been opened and the force applied to the rod 46 through either of the handles 48 or 50 is relieved, the spring 52 restores the rod 56 to the position shown, thus automatically opening the circuit.

All of the doors may be locked from either side of the exterior of the car by manipulating either switch 16 or 26 with a suitable key. This opens the circuit to the conductors 38 and consequently the closing of any of the switches 42 does not complete the circuit to the solenoid and therefore the latch bolt is not withdrawn. When the driver returns to the car he may unlock the doors by manipulating either switch 16 or 26, regardless of which switch was manipulated in order to lock the doors.

If it is desired to lock the doors from the inside of the car this may be done by opening the switch 34 which is located preferably on the dash within easy reach of the driver.

A conductor 72 is connected to conductor 32 and to the contact 74 of a two-point break and five-point make push button designated generally by reference character 76. The push but-

ton includes a contact member 78 which is spring biased into its upper position so as to normally complete a circuit between contact 74 and a contact 80. Contact 80 is connected by means of a conductor 82 to a normally closed contact 84 on a similar push button switch 86. The other normally closed contact 88 of this switch is connected to a conductor 90 which leads to the switches for controlling the operation of the window actuator motors. Switch 76 is preferably located on the exterior of the car body closely adjacent to one of the key operated switches 16 or 26, while the switch 86 is located adjacent to the other key operated switch.

Conductor 90 is connected to the blade of a double throw switch 92 which is provided with spring means for biasing the blade to an open position out of contact with the poles 94 and 96 of the switch. A conductor 98 is connected to pole 94 and is taken into one of the front doors of the car through a suitable flexible lead or plunger contact 100. Interposed in the conductor 98 within the door is an upper limit switch 102 which is shown diagrammatically in Fig. 1 and more in detail in Fig. 5. From the limit switch conductor 98 leads to one terminal of a reversible electrical motor 104, another terminal of which is grounded. A conductor 106 leads from contact 96 of switch 92 through a lower limit switch 108 to the third terminal of motor 104. The construction of this motor is such that, when current is supplied to it through conductor 98 and the ground connection, it rotates in one direction, while the supply of current through the conductor 106 and the ground connection causes it to rotate in the opposite direction.

This motor drives a screw jack 110 through suitable gearing 112, preferably of the worm type. The screw 110 engages an internally threaded member 114 which is secured to a bracket or the like 116 which carries a window 118. Also secured to the bracket 116 is an arm 120 which is arranged to strike the plunger of upper limit switch 102 when the window is in fully closed position. This arm is also arranged to strike the plunger of lower switch 108 when the window is in fully opened position.

Similar wiring is provided for the other window in the other front door and the two switches 92 are preferably located near the center of the dash so as to be within easy reach of both the driver and the passenger in the front seat.

It is desirable to be able to actuate the windows in the rear doors either from the driver's seat or from the rear seat. Consequently, conductor 90 is connected to the blade of a switch 120 located within reach of the driver. This switch is provided with contacts 122, 124, and 126, the blade being spring biased so as to normally complete the circuit through contact 124. This contact is connected by means of a conductor 128 with the blade of a switch 130 which is located in the tonneau so as to be easily accessible to the passenger sitting next to the door window which is controlled thereby. This switch is provided with contacts 132 and 134 and the blade is spring biased so as to normally occupy a neutral open position. Contact 132 is connected by means of a conductor 136 with the conductor 98 leading into the door and in which is interposed the upper limit switch 102. A conductor 138 connects contact 134 with conductor 106 which leads into the door and in which is interposed the lower limit switch 108. The same switches and connections are repeated for the other rear door,

the switch 130 being within easy reach of the passenger in the rear seat adjacent to this door, while the switch 120 is accessible to the driver.

In order to regulate the position of the front windows, either the driver or the front seat passenger may manipulate the switches 92. If one of these switches is closed in its upper position, current from the battery is supplied through switches 16 and 26, conductors 32, and 72, push button switch 76, conductor 82, push button switch 86 and conductor 90 to the blade of switch 92. From here the current passes through the pole 94, conductor 98, connection 100 and upper limit switch 102, which is closed except when the window is in its uppermost position, to motor 104. This causes the motor to operate in the proper direction to raise the window. If the window already is fully raised when the switch 92 is closed, the limit switch 102 is open and obviously the motor will not start, and no damage can result. Otherwise, the motor continues to raise the window as long as switch 92 is held closed, and thus the position of the window may be regulated and if it is desired to fully close the window, the switch 92 is maintained closed until the limit switch 102 is opened to stop the motor. In the same way, the window may be opened any desired amount by closing the switch 92 in its lower position so as to complete the circuit through the contact 96.

If a rear seat passenger wishes to regulate one of the rear windows, this may be done by manipulating the proper switch 130. If a switch 130 is closed in its upper position the circuit is completed from conductor 90 through contact 124 of switch 120, conductor 128 and contact 132 of switch 130 and conductor 136 to conductor 98, thus causing the motor to operate in the proper direction to raise the window. If the driver wishes to regulate a rear window he may do so by manipulating the proper switch 120. If this switch is thrown out of its neutral position it opens the circuit to the switch 130, thus rendering the latter temporarily ineffective to control the motor 104. This is highly desirable in order to avoid the possibility of the switch 120 being closed in a position to drive the motor in one direction at the same time that the switch 130 is closed to drive it in the opposite direction. The construction of the reversible motor 104 is such that, if this were to occur, the motor would be rapidly overheated and if the condition continued for any length of time it might burn out the motor.

It will be noted that the above described circuit to the window actuator motors 104 passes through the key operated switches 16 and 26. Consequently, if the car doors have been locked by opening the circuit through these switches, the various manual switches 92, 120, and 130 are ineffective to raise or lower the windows. Hence, if the car has been left with the windows slightly open, as is common practice in the summer time in order to provide a slight amount of ventilation for preventing the interior of the car from getting excessively hot, an unauthorized person cannot open a window by manipulating one of the manual switches by means of a long stick or the like introduced through a slightly open window.

Push buttons 76 and 86 are provided so as to enable the operator to close all the windows which may be open at the time he locks the car by manipulating one of the switches 16 or 26. A conductor 140 leads from the conductor 14 to

one of the five normally open contacts of each of switches 76 and 86. The other four normally open contacts of these switches are connected in parallel to conductors 142, 144, 146, and 148, respectively, each of which conductors is connected to one of the conductors 98 leading to the upper limit switch 102 of each door. Thus, if either of the push button switches 76 or 86 is depressed, a circuit is completed from the battery through conductors 14 and 140 to the conductors 142, 144, and 146 and 148, thus causing all the motors 104 to run in the proper direction to close all the windows. If the push button is held closed long enough, all of the windows will be completely closed and as each window is closed it will actuate the upper switch 102 so as to stop its motor. If it is desired to leave one or more windows opened slightly, this may be done by releasing the push button switch just before such window or windows are fully closed.

It will be noted that when either of the push button switches 76 or 86 is depressed so as to raise all the windows, the circuit through the conductor 90 to the interior switches 92, 120, and 130 is automatically interrupted and the switches are rendered temporarily ineffective. Thus, if one of the push button switches is operated so as to close the windows, none of the interior switches can be operated so as to tend to open a window. While there is little likelihood of accidental simultaneous operation of a push button switch and an interior switch, it might occur if the car were left unattended, but unlocked so that children could play with the switches.

As shown in Fig. 1, inasmuch as conductor 140 is connected directly to the battery line 14, push button switches 76 and 86 are operable to close the windows, regardless of whether the circuit through switches 16 and 26 is closed or open. This is usually desirable as the operator is thus enabled to close all the windows either before or after he has locked the doors, and unauthorized manipulation of a push button can only result in further closing any window which is not already fully closed. However, if it is desired to render the push button switches inoperative when the doors are locked, this may be accomplished readily by merely transferring the connection of conductor 140 from conductor 14 to conductor 32.

While I have shown and described a preferred embodiment of my invention, it will be understood that this has been done for illustration only and that the scope of my invention is not to be limited thereby, but is to be determined by the appended claims.

What I claim is:

1. In a system for the electrical operation of a plurality of vehicle doors and windows, an electrically releasable latch for each door, electrically operated means for opening and closing each window, an individual switch in the circuit of each of said latches, and in the circuit of each of said electrically operated means, a source of electric current, a key operated master switch accessible from the exterior of said vehicle and connected between said source of current and all of said individual switches, and a manually operable switch located within said vehicle and connected between only said key operated switch and the individual switches in the circuits of said latches.

2. In a system for the electrical operation of a plurality of vehicle doors and windows, a latch member for each door, a source of electric current, means for urging each latch member into

latching position, a solenoid for retracting each latch member, a reversible motor for opening and closing each window, individual switching means in the circuit of each solenoid and accessible for operation on both sides of the respective doors, 5 an individual two position switch in the circuit of each of said motors and located within said vehicle, a key operated master switch located at the exterior of said vehicle and connected between said source of current and the several switching means and the several two position switches, and a manually operable switch located within said vehicle and connected between only said key operated switch and said several switching means.

3. In a system for the electrical operation of a plurality of vehicle doors and windows, an electrically releasable latch for each door, electrically operated means for opening and closing each window, an individual switch in the circuit of each of said latches, and in the circuit of each of said electrically operated means, a source of electric current, a key operated master switch connected between said source of current and the several individual switches for rendering the latter inoperative to actuate the respective latches and electrically operated means, and a manually operable master switch for establishing a circuit independently of said key operated switch and of said individual switches between said source of current and each of said electrically operated means for actuating the latter simultaneously to close all of said windows.

4. In a system for the electrical operation of a plurality of vehicle doors and windows, an electrically releasable latch for each door, an individual switch in the circuit of each of said latches, a reversible motor for opening and closing each window, a source of electric current, an individual three position switch in the circuit between 35 said source and each motor, a key operated master switch in series between said source and each of said individual switches for rendering the latter inoperative to actuate the respective

5 latches and motors, and a manually operable master switch for establishing a circuit, independent of said key operated switch and of said individual switches, between said source and each of said motors for operating the latter simultaneously to close all of said windows.
